UNITED STATES PATENT OFFICE

HARVEY O. MILLER, OF CHICAGO, ILLINOIS

DESIGN FOR A DEVICE FOR SCRAPING AND CLEANING THE FACE OF A GOLF CLUB

Application filed March 2, 1931. Serial No. 38,888. Term of patent 7 years.

To all whom it may concern:

Be it known that I, HARVEY O. MILLER, a citizen of the United States, and resident of Chicago, in the county of Cook and State of Illinois, have invented a new, original, and ornamental Design for a Device for Scraping and Cleaning the Face of a Golf Club, of which the following is a specification, reference being had to the accompanying drawings, forming a part thereof.

Figure 1 is a view in perspective of a device for scraping and cleaning the face of a golf club showing my new design, with the guard therefor shown in open position;

Figure 2 is a front elevational view of the same with the guard therefor shown in closed position; and

Figure 3 is a rear elevational view of the same with the guard therefor shown in closed position.

I claim:

The ornamental design for a device for scraping and cleaning the face of a golf club substantially as shown.

Signed at Chicago, in the county of Cook and State of Illinois, this 21st day of February, A. D. 1931.

HARVEY O. MILLER.
